UNITED STATES PATENT OFFICE.

ASA SCHNEE, OF JONESBORO, ARKANSAS.

COMBINED SUPPORT, DEFLECTOR, AND HOUSING FOR MOTOR-DRIVEN FANS.

1,372,251.

Specification of Letters Patent. Patented Mar. 22, 1921.

Application filed February 28, 1920. Serial No. 361,985.

To all whom it may concern:

Be it known that I, ASA SCHNEE, a citizen of the United States, residing at Jonesboro, in the county of Craighead and State 5 of Arkansas, have invented certain new and useful Improvements in Combined Supports, Deflectors, and Housings for Motor-Driven Fans, of which the following is a specification, reference being had to the accompanying drawings.

This invention relates to an improved combined housing, support and deflector for motor driven fans, and an object of the invention is to provide a device of this kind 15 which is very simple, efficient and practical in construction and portable from one place to another. Furthermore, the device is capable of being cheaply constructed, whereby it may be sold at a reasonable profit.

20 The invention further aims to provide a combined support, housing and deflector, whereby the motor driven fan can be supported on a table, obscured from sight and whereby the air is deflected laterally and 25 upwardly so as to scatter to all parts of the room and maintain the atmosphere of the room refreshing and cool.

The invention still further aims to provide a combined deflector and support in the 30 form of a base having a central conical or cone shaped portion axially aligned with center of the shaft of the motor, whereby the air passing downwardly from the blades of the fan is deflected radially from the cone 35 shaped portion and partially upwardly by the base thereby causing the air to circulate over the room.

While the design and construction at 40 present illustrated and set forth is deemed preferable, it is obvious that as a result of a reduction of the invention to a more practical form for commercial purposes, the invention may be susceptible to changes, and the right to these changes is claimed, provided they are comprehended within the 45 scope of what is claimed.

The invention comprises further features and combination of parts, as will be herein-after set forth, shown in the drawings and 50 claimed.

In the drawings:—

Figure 1 is a view of a table showing the improved combined support, deflector and housing for the motor driven fan mounted 55 upon a table.

Fig. 2 is a vertical sectional view through

the combined support, deflector and housing constructed in accordance with the invention; and

Fig. 3 is a plan view.

60 Referring to these drawings, 1 designates a combined base and deflector which in the present instance is hollow, and of circular form. The central portion of the supporting base and deflector has a gradual conical or cone shaped portion 2, the center of which is axially concentric with the shaft 3 of a conventional form of electric motor 4. The shaft 3 of the motor has a revoluble fan 5 and as this fan rotates, the air is agitated 65 and forced in the direction of the central conical cone shaped portion 2. The upper wall of the base merges from the conical or cone shaped portion outwardly and radially and slopes slightly upwardly and merges 70 into a marginal raised or bulged portion 6, which is on the plane substantially with the height of the cone or conical shaped portion 2. The air from the fan is deflected outwardly and downwardly and then outwardly 75 and gradually upwardly so as to circulate to all parts of the room.

By means of supports 7 either integral with or detachably fastened to the upper wall of the base, a hood or cover 8 is supported in a spaced superimposed position relatively to the base. Adjacent the top of the hood or cover housing is a plurality of apertures or openings 9, arranged circumferentially of the cover or housing in order 80 to permit air to enter the housing so as to be acted upon by the revoluble fan. The electric motor 4 which may receive electric power from any suitable source of supply, not shown, is supported by the arms or 85 brackets 10 from the inner circumference of the housing as clearly shown in the sectional view. 11 and 12 denote the connections leading to the motor, for conveying a current of electricity thereto. A conventional 90 form of switch 13 is mounted upon the interior of the housing with its operating switch 14 passing through the slot 15 of the housing for turning on and off the current. This switch is provided with the usual electrical conductors 16 to the motor in order to 95 control the current. Suitable supporting feet or nubs 17 are carried by the under portion of the marginal edge of the base to engage with the surface of the table 18 to support the entire apparatus. These supporting nubs or feet are constructed of rubber 100

110

or any other suitable material so as to prevent marring the surface of the table.

The invention having been set forth, what is claimed as new and useful is:

- 5 1. The combination with an inverted motor driven fan, of a housing therefor, means within the housing and engaging the casing of the motor for supporting the motor driven fan, a base on which the housing is supported, said base having a central cone provided with a bearing to receive the shaft of the motor driven fan, the lower edge of the housing being spaced from the base to permit the air from the fan to pass
- 10 15 from under the housing, the upper surface of the base merging from the cone radially and upwardly and to a marginal raised portion disposed in a plane substantially parallel with the top of the cone, thereby

deflecting the air laterally outwardly and 20 upwardly to circulate to all parts of a room.

2. In a device as set forth, a base having a central cone, an inverted motor driven fan having its fan shaft engaging in a bearing of said cone, a housing for the fan having 25 legs engaging the base, means connected to the wall of the housing, and to the motor of the fan for holding the motor driven fan concentric with the housing and the base, the upper surface of the base extending 30 radially and upwardly from the cone and terminating in a marginal raised portion disposed in a plane substantially parallel with the top of the cone, thereby deflecting the air radially outwardly and upwardly. 35

In testimony whereof I hereunto affix my signature.

ASA SCHNEE.
